WRAPPING MACHINE

John A. Heckman, Chicago, Ill., assignor to Miller Wrapping and Sealing Machine Company, Chicago, Ill., a corporation of Illinois

Application November 17, 1941, Serial No. 419,385

14 Claims. (Cl. 93—2)

The machine of the present invention is designed to apply a wrapper of paper, Cellophane, or the like, to boxes or packages, preferably of rectangular shape, which are fed forwardly in processional relation to the wrapping point, and are there surrounded by a wrapper section cut from a continuous web fed transversely of the machine to a point where its center will register with the underlying package, after which the package will be elevated beneath the body of the wrapper, allowing the margins thereof to drape downwardly in position to have their edges overlap beneath the base of the package, after which the end wrapper extensions are tucked inwardly along the bottom and sides, which partially completes the wrapping operation at an intermediate level. Thereafter, the partially wrapped package is lifted to a higher level, which folds down the wrapper flaps projecting from the top of the package, thus completing the folding operation in preparation for a heat sealing operation, which occurs at the highest or discharge level and thus completes the operation in preparation for the discharge of the wrapped package.

The machine as a whole is designed to perform the package feeding and wrapper feeding operations automatically and in properly timed relation, and to perform the flap tucking sequence at the proper time and at the proper level so that all operations involved in the complete wrapping and sealing of the package are automatically performed.

The machine is also designed to permit the necessary adjustments to accommodate the wrapping of packages of varying size, without altering the order and sequence of operations, and in a manner which insures the proper centering of a wrapper section with respect to the package, regardless of the size thereof, so that in all cases, regardless of adjustments, the various movements will conform to the basic principle of operation, and the proper timing and range of movements of the parts will be maintained.

Further objects and details will appear from the description of the invention in conjunction with the accompanying drawings, wherein,

Figure 1 is a side elevation of the entire machine as viewed from the position occupied by the operator, with the infeeding mechanism for the unwrapped packages projecting toward the left or front end of the machine, and it will be understood that in the principal views the machine is viewed from a similar position;

Fig. 19 is a similar view showing the operating parts in a different position of adjustment;

Fig. 20 is a sectional detail of the ratchet mechanism for operating the sheet feeding and delivering mechanisms, in one direction only;

Fig. 21 is a detail of said ratchet mechanism and associated parts;

Fig. 22 is a detail showing the cams and associated mechanisms for feeding the packages inwardly to wrapping position and for operating the elevator to lift the packages to the different stages of elevation;

Fig. 23 is a detail showing the cams and associated mechanisms for operating the folder blades which fold the depending sides of the wrapper inwardly across the base of the package in overlapped relation;

Fig. 24 is a sectional detail of one of the wrapper blades with its surrounding sheath of fabric to prevent displacement of the underlying wrapper edge during the withdrawal of the folder blade;

Fig. 25 is a view similar to Fig. 23, showing the position of the parts just prior to the instant of withdrawal of the forward folder blade;

Fig. 26 is a detail showing the cams and connections for the elevator and the tucker blades for upfolding the projecting ends of the wrapper against the ends of the package, and for infolding the wrapper flaps across the ends of the package;

Fig. 27 is a similar view showing the tucker blade in a different position of adjustment;

Fig. 28 is a plan view of the wrapper after the completion of the tucking operation illustrated in Figs. 26 and 27, with the final end flaps projecting from the top of the wrapper;

Fig. 29 is a similar view showing the movements involved in lifting the wrapper to the highest level, and illustrating the heater for sealing the wrapper, and the cooler for thereafter withdrawing excess heat;

Fig. 30 is a similar view, illustrating the operation of the pushers for ejecting the completely wrapped package from the elevator to the heat sealing position;

Fig. 31 is a detail taken on line 31—31 of Fig. 3, illustrating the variable speed drive mechanism for regulating the speed of the operating parts;

Fig. 32 is a detail taken on line 32—32 of Fig. 3, showing the one-way drive in the train of transmission; and

Fig. 33 is a perspective view showing the frame mountings for permitting coordinated adjustment of the operating parts.

Package feeding mechanism

The operating features of the present machine are housed within a frame comprising spaced side plates 48 and 49, which are suitably connected by front and rear upper bridge bars 42 and 43 and lower bridge bars 44, and in other suitable manner to afford a rigid open frame for the reception of the operating parts and their support.

At the front or intake end of the machine is located a forwardly projecting feeding table 45, shown in Figs. 1, 2, 4, 5 and 6, which is provided

with channels 46 and intervening ridges 47 in its upper surface, along which moves a carrier comprising spaced feed rods 48 carried by endless chains 49 mounted upon front and rear sprockets 50 and 51. The feed rods on the upper turn of the carrier ride upon the ridges and afford abutments for the carrying forward of the rectangular boxes or packages P (Fig. 4), which are held in position by pairs of spaced side guide bars 52 carried by front and rear cross rack bars 53 and 53^a slidably mounted within front and rear brackets 54 and 54^a, both mounted upon spaced fixedly suspended spaced side rails 54^b, which arrangement permits the guide bars to be adjusted laterally to accommodate them to packages of varying length (Fig. 33), in conformity with a principle of general adjustment which will hereafter be described in detail.

In order to stop the operation of the machine when the spaces between the feed rods 48 are empty, a trip bar 55 is provided which is mounted upon links 56 (Fig. 4) and backed by a light spring 57 of sufficient strength to elevate the trip bar 55, when not depressed by the weight of a package or by the contact of one of the feed rods.

The rear link 56 carries a dog 58 which bears upon a tilting plate 59 carrying a mercury switch 60 controlling the circuit (not shown) leading to a motor 61 (Fig. 3). When the trip bar is depressed by the weight of a package, as shown in Fig. 4, it will elevate the tip of the dog 58, thereby tilting up the mercury switch and closing the motor circuit, but if no package is delivered to the carrier, the trip bar will be thrust upwardly when relieved of the contact of a passing feed rod, which upward movement will tilt the plate 59 carrying the mercury switch and open the motor circuit, thereby stopping the operation of the machine.

One of the endless carrier chains 49 is elongated and passes over upper idler sprockets 62 and lower idler sprockets 63, and thence inwardly to a feed sprocket 64 carried by a main cam shaft 65 (Fig. 3), which constitutes the centralized agency for distributing power to the various operating mechanisms.

In order to adjust the side guide bars 52 in and out in unison, they are suspended at their inner ends from hangers 66 (Fig. 33) which depend from adjusting heads 67 which are operated to move in unison toward and from one another in a manner presently to be described in effecting certain transverse adjustments required to adapt the machine to the wrapping of boxes of different lengths. The inner racks 53^a mesh with pinions 67^a on companion shafts 67^b which carry pinions 67^c at their forward ends meshing with the racks 53, so that transverse adjustments imparted to the rear ends of the guide bars 52 will be imparted through the racks equally and uniformly to the forward ends.

Elevator mechanism

The packages are fed inwardly in the manner described, and are delivered at the lowermost level on to an elevator 68 (Figs. 4 and 22) which is located in the operative center of the machine; that is to say, at the point where the longitudinal feeding axis for the packages intersects the transverse feeding axis for the wrappers. The elevator is carried by a bracket 69 springing upwardly from a slidable head 70 which forms a portion of a movable frame 71 mounted upon upper and lower rollers 72 and 73 journalled

within arms 74 carried by a vertical post 75, the arrangement being one which permits the frame to travel vertically under the thrust of a link 76 pivoted at its upper end to the head 70, and at its lower end to an oscillating arm 77, the rear end of which is mounted upon a fixed pivot 78 and carries a roller 79 operable within a cam track 80 formed in the face of an elevator cam 81 mounted upon the cam shaft 65.

Fig. 22 shows in dotted lines the upper position to which the elevator will be moved by the operation of the cam, which, however, constitutes the intermediate of three vertical positions occupied by the package during its vertical progression through the machine. In the lowermost position illustrated in Fig. 22, the elevator is aligned with the discharge end of the package feeding mechanism, and in view of the fact that packages of differing width must be accommodated, the elevator is made removable from the head 70, so that others of different dimensions may be substituted, as occasion may require.

The wrapper feeding mechanism

The wrapper material, paper, Cellophane or the like, is carried in the form of a continuous roll of web W carried by a spindle 82 (Figs. 2 and 8) mounting spool heads 83 and 83^a, the former of which is adjustable on the spindle. The spindle is mounted between brackets 84 and 85 extending outwardly from the far side of the machine, the ends of the spindle being supported upon roller bearings 86 (Fig. 8), the forward bearings engaging a groove 86^a in the spindle, which permits the spindle to be precisely adjusted endwise by the thrust of an adjusting screw 86^b (Fig. 2), and in order to prevent overrunning of the web during the infeeding of the wrapper sections, a brake shoe 87 is provided which bears against a brake drum 88 on the spindle. The brake shoe is carried by an L-shaped arm 89, the upper arched end 90 of which is pivoted at 91 to the bracket 85, the lower elongated end 92 of the arm carrying a lever 93 pivoted at 94 and having its upper end engaged by a spring 95 which runs upwardly and connects with the brake arm 92.

The web is fed downwardly between upper and lower idle rolls 96, thence downwardly and around a vertically yieldable roll 97 carrying at each end a pinion 98, which pinions mesh with vertical racks 99, so that, in moving vertically, the roll 97 will not be tilted or canted from its horizontal position. The roll 97 is relatively heavy and acts to maintain tension on the web, and at one end the roll finds a bearing within the hooked end 93^a of the lever 93, so that when the roll is in its lowermost position as indicated in Fig. 8, it will serve to impart a downward pressure through the brake arm 89 and impose a braking action on the drum, thereby preventing overrunning of the web while being fed. At the same time, in the starting of the machine, a sudden forward pull will be imparted to the web which must overcome the inertia of the wrapper spool, and in this event the tension of the web will tend to elevate the roll and thus relieve the brake arm of its weight, thereby allowing the brake arm to swing on its pivot 91 and release the braking contact. Similarly, in the event the web becomes jammed in the spool, so that it does not feed under tension, the roll 97 may lift to relieve the tension and prevent breaking of the web.

The web passes upwardly from the roll 97 around an idle roll 100, then around a rubber faced power driven feed roll 101 and under a presser roll 102, and thence is delivered inwardly 5 in a horizontal direction toward the center of the machine. The presser roll has trunnions 101^a (Fig. 9) which are journaled within the hooked ends of brackets 101^b and held in place by friction lock bars 101^c, the brackets being centrally pivoted between arms 101^d and held in normal position by the tension of springs 101^e, which arrangement permits the roller 102 to be lifted to thread the web through the machine or to be readily removed by retraction of the 15 lock bars. The web delivered from the feed roll is carried forward by endless conveyor tapes 103 in spaced relation to one another as shown in Fig. 7, each of which tapes travels upon a supporting plate 104 (Fig. 7) and is carried around 20 an outer idle roll 105 and an inner power driven pulley 106 mounted upon a wrapper delivery shaft 107.

At a point intermediate the feed roll 101 and the idle roll 105 is located cutting mechanism 25 which comprises a fixed horizontal shear blade 108 and a pivoted vertical shear blade 109 (Figs. 8, 13, 15, 16 and 17). The movable shear blade is pivoted at its outer end, and its cutting edge normally extends in slightly oblique relation and below the edge of the fixed blade (Fig. 16), providing a gap for the advance of the web. The free or unpivoted end of the shear blade has connected thereto a rod 110, the lower end of which is pivoted to the free end of a lever 111 30 by a ball and socket fitting 112. The lever 111 is pivoted at its center 113, and at its opposite end carries a roller 114 which is adapted at recurrent intervals to be engaged by a cam projection 115 carried by a pusher cam 116 mounted upon the cam shaft 65 (see also Fig. 3). The wrapper sections severed from the web are necessarily of much greater length and width than the top surface of the package to be wrapped, so that their ends and sides project beyond the 45 ends and sides of the package, as indicated by the dot and dash lines of Fig. 1.

The delivery arrangement employed is one which affords an open or unobstructed space which is bridged by the body of the wrapper, 50 whose ends lie upon the delivery tapes and are held firmly against accidental displacement by relatively heavy balls 117 (Fig. 8) which are individually loosely caged within a plurality of parallel ball race bars 118 (Fig. 7), so that they 55 will bear upon the fore and aft extensions of the wrapper with sufficient weight to prevent sagging in the center, and thus maintain the wrapper against the delivery tapes, which advance them to wrapping position, while the ends of the wrapper are supported on spaced grid bars 118^a (Figs. 22 and 26).

It will be understood that the machine must provide for the delivery of wrapper sections of varying widths (transversely of the machine), 65 and that, irrespective of width, each wrapper section must be delivered to a position such that its computed folding center (which need not be its geometrical center) will register with the center of the package for which it is intended, 70 and by reason of this circumstance it is necessary that provision be made to vary the range of each feeding movement of the roll which feeds the web, and also the range of the delivery movement of the severed wrapper sections, and the 75 feeding and delivery movements must necessarily

harmonize with one another. To attain these results, the following mechanism is provided:

The feed roll 101 is actuated by a sprocket chain 119 (Figs. 7 and 20), which in turn is actuated by a sprocket chain 120 driven by a sprocket 121 freely carried by a shaft 107 which actuates the delivery tapes.

In the operation to be performed, it is necessary that the web feeding roll and the delivery tapes move forward at uniform feeding speed until the wrapper section has been severed, after which the movement of the web feeding roll must be arrested while the inward travel of the delivery tapes continues. The ratchet mechanism shown in Figs. 20 and 21 is designed to meet these requirements.

The shaft 107 has keyed thereon at its outer end a chambered head 122, which houses ratchet rollers 123 of the well known character shown in Fig. 21, which, by wedging, impart a feeding movement in one direction only, and which need not be further described in detail.

The chambered head carries a brake drum 124 overlapped by a brake band 125 to prevent overrunning of the parts, and the ratchet rolls coat with a sleeve 126 freely mounted upon the shaft 107 and carrying a sprocket wheel 127 which mounts an endless chain 128 adapted to be moved vertically by a sheet delivery arm 129 carrying a lug 130 which is fast to one of the turns of the chain, so that a feeding movement in the upper direction will, through the roller-ratchet assembly, impart rotation to the shaft 107 for the purpose of imparting the complete range of movement to the shaft required in first receiving the leading end of the web before severing, and in thereafter continuing the delivery movement required in bringing the severed sheet to register with the center of the folding area.

The brake band 125 (Fig. 18) is tightened by the pull of a draw rod or cable 125^a connected with the short arm of a bell crank lever 125^b carrying at its opposite end a roller 125^c adapted to be momentarily engaged by a cam block 125^d carried by the sheet delivery cam 159 presently to be described.

At the inner end of the ratchet feeding assembly is located an inner head 131, which is keyed to the shaft 107 and chambered to afford a runway for roller bearings 132 which bear against a sleeve 133 having a medial rib 134 to which is bolted the sprocket wheel 135 driven by an endless chain 136 moved vertically by a web feeding arm 137 carrying a lug 138 which is fast to one of the turns of the chain 136, being the turn which is opposite to that of the chain 128 to which the lug is attached.

The sleeve 133 coacts with a hub 139 to which is bolted the sprocket wheel 121 which carries the drive chain 120 for rotating the web feeding rubber faced roll 101; and interposed between the sleeve 133 and the chambered face of the hub 139 are ratchet rollers 140 and 142 of the character heretofore described, which impart movement in one direction from the chain 136 through the ratchet assembly to the chain 129 which drives the feed roller and also the roller 132, which drives the shaft 107 through the chambered head 131.

The hub 139 carries a brake drum 139^a mounting a brake band 139^b connected with a rod or cable 139^c engaging a bell crank 139^d having a roller 139^e momentarily actuated by a cam lug 139^f on the web feeding cam 172 presently to be described. During the inward advance of the

web, the feed roller and the tapes will travel at the same feeding speed.

It will be noted that in respect to the operation of the web feed roll 101, the shaft 107 merely affords a bearing for the rotation of the parts, but that in the driving of the tapes and ultimate delivery of the severed sections, the shaft 107 acts to transmit rotation from the vertical chain 128 to the pulleys 106 which carry the tapes. Figs. 18 and 19 illustrate the means provided for imparting vertical feeding movements to the chains 128 and 136.

The arm 129 which engages the chain 128 is pivoted at its rear end to a link 141, the lower end of which is pivoted upon a fixed pivot 142; and the arm at an intermediate point is pivoted to the upper end of a link 143, the lower end of which is pivoted upon a fixed pivot 144. The arm at a point between the fixed pivot 144 and the end link 141 is connected with a vertical lever 145, which is pivoted to the arm at an intermediate point 150.

The lower end 151 of the lever carries a roller 152 which is adjustable within a groove 153 in a rocking arm 154 pivoted on a fixed pivot 155 and terminating at its forward end in an angularly disposed arm 156, which carries a roller 157 operating within a groove 158 in the face of a sheet delivery cam 159 on the cam shaft 65 (Fig. 3). The upper end 160 of the vertical lever is bored to receive a lever extension rod 161 which is telescoped into the lever end 160 and constitutes a portion of an adjusting assembly, which permits the vertical lever 145 to be rocked so as to shift the position of the roller 152 within the grooved rocking arm, thereby adjusting the distance of the roller from the fixed pivot 155 in order to regulate the extent of the feeding movement imparted to the lever 145, and thence through the arm 129 to the vertical chain 128.

Similarly, the arm 137 is pivoted to the upper end of a link 162 carried by the fixed pivot 142, and is supported medially by a link 163 mounted upon the fixed pivot 144. The arm 137, in a similar manner, is pivoted to a vertical cross lever 164, the lower end 165 of which carries a roller 166 adjustably mounted within a groove 167 in a rocking arm 168 carried by the fixed pivot 155 and terminating in a forward lever arm 169 carrying a roller 170, which operates within a cam groove 171 in the face of a web feeding cam 172 mounted on the cam shaft 65. The upper end 173 of the vertical lever 164 likewise receives a telescopic extension 174 which constitutes part of the adjusting assembly for regulating the extent of the reciprocating movement imparted through the lever 137 to the chain 136, which withdraws the web from the spool on the down stroke of the chain.

60 Feeding and delivery adjusting mechanism

Reference has been made to the fact that the range of the web feed and the range of the wrapper delivery movement may be varied to accommodate variations in the length (transversely of the machine) of the wrapper section, and to insure that each wrapper section, regardless of size, will be centered at the center point in the folding section of the machine. In the case of a relatively long wrapper section, it will be necessary to correspondingly lengthen the range of the feeding movement of the feed roll 101, and correspondingly or inversely reduce the supplemental conveying movement afforded by the tape conveyor after the wrapper section has been sev-

ered and to reverse the range of these movements where a relatively short wrapper section is being cut off and delivered. To meet these requirements, the adjustments imparted to the upper telescoping ends of the vertical lever arms 145 and 164 will be in opposite directions, so that, as the range of movement of either is increased, the range of movement of the other will be correspondingly decreased, and the adjusting mechanism now to be described conforms to this requirement.

The mechanism is best illustrated in Figs. 11, 12, 18 and 19. It consists of mechanism supported by brackets 175 and 175^a secured to the inner face of the front side wall 40 of the machine near the top thereof. Each bracket is provided with a hanger 176 between which extends a bar 177 which pivots the lower end of an arm 178 slotted at its upper end 179 to receive the projecting end of a pintle 180 which extends through ears 181 depending from a rider 182 slidably mounted upon a guide rod 183 having its ends supported within a portion of the brackets 175 and 175^a.

The rider 182 is provided with an upstanding boss 184 into which is threaded the lower end of a handle 185 which projects upwardly beyond the front side wall of the machine within convenient reach of the operator. The handle is surrounded by a coil spring 186, the upper end of which is entered into the handle and the lower end of which is entered into the boss, and the lower threaded end of the handle normally frictionally engages the rod 183 under spring tension so as to hold the rider in adjusted position while permitting a reverse or unscrewing movement of the handle against spring tension to release the frictional contact and permit adjustment.

The pintle 180 affords a pivot mounting for the telescoping extension carried by the upper end 173 of the lever 164.

The pivoted arm 178 has secured to its inner face a block 187 which engages the outer turn of an endless cable 188 which passes around sheaves 189 journaled in each case between ears 190 inwardly extending from a head plate 191 (Fig. 11), which head plates are connected by rods 192, thus forming an open rectangular inner frame connected at its ends to the brackets 175 and 175^a, respectively.

The opposite turn of the cable 188 passes through and is rigidly connected to a block 193, from which upwardly extends an arm 194 which receives one end of a pintle 195 which passes through a block 196 and through the upper end of the extension 161 which telescopes into the upper end of the lever 145, furnishing a pivotal mounting therefor, and thence into a short slide bar 197, which is movable within a fixedly mounted guide channel 198 and cooperates with a similar slide bar 199 movable within a fixedly mounted guide channel 200, supported by the head plates.

The rider boss 184 carries an upwardly extending arm 201 terminating in an angularly disposed pointer 202 which is movable along the surface of a graduated gage bar 203 having markings thereon to indicate the movements required to adjust the machine to wrappers of varying length.

With the mechanism shown, a movement of the rider 182 in either direction will directly impart a swinging movement to the upper end 173 of the lever 164 which controls the extent of movement imparted by the feed roll 101 to the web. The rider movement will at the same time, through the swinging of the lever arm 178, impart

a corresponding movement in the same direction to the proximate turn of the cable 188, which, however, is transformed into a reverse movement imparted to the lever 145 through the arm 194 and the pivotal connection with the telescope extension 161 which controls the range of movement required in bringing the severed wrapper sections into register with the center of the folding area.

Folding mechanisms

With the elevator 69 in the lowermost position as shown in Fig. 22, and with a package supported thereon, the severed wrapper section will be fed transversely above the package to the position indicated by the outer dot and dash lines in Fig. 7, with its folding center in coincidence with the center of the package, and with its end and side margins projecting beyond the package to the degree required to first fold the ends of the wrapper down and around the sides of the package and into overlapping relation along the bottom of the package, and with the side margins of the wrapper projecting sufficiently to permit the formation of bottom, top, and side folded flaps across the ends 25 of the package.

The vertical movement imparted to the elevator 68 by the mechanism shown in Fig. 22 will elevate the package to the extent illustrated in dotted lines in said figure. This elevation causes the top of the package to engage the center of the tensioned wrapper sections W', the ends of which are slidably held taut by the weight of the balls 117. This causes the ends of the wrapper to sweep past a pair of spaced bars 204 and thus 35 drapes the ends of the wrapper downwardly around the sides of the package and along the edges of spaced folder blades 204 and 205 (Figs. 22, 23, 24 and 25). The folder blades stand in their outer or withdrawn position in Fig. 22, and 40 are shown at the completion of their inward folding stroke in Fig. 25. The folder blades are removable for replacement of different sized blades to accommodate packages of different lengths.

The folder blade 204 which later serves as a 45 secondary elevator has a longer stroke imparted to it than the blade 205, but the blade 205 completes its folding stroke before the stroke of the blade 204 is completed, so that the margin of the wrapper carried in by the folder blade 204 will 50 overlap the flap carried inwardly by the folder blade 205. In order that the underlying flap may not be withdrawn by the return movement of the folder blade 205, the folder is constructed in the manner shown in Fig. 24, being surrounded by a 55 sheath 206 of fabric, the ends 207 of which are clamped within a fixed cross bar 208, and the sheath is carried around front and rear rollers 209 and 210, so that as an inner thrusting movement is imparted to the folder blade, the surface 60 of the sheath will be rolled out under the margin of the wrapper, with the result that on the return stroke the contacting fabric surface will be simply rolled away from contact with the wrapper margin and without developing any friction which 65 might tend to displace and withdraw the under tucked wrapper edge.

The folder blades 204 and 205 rest upon the upper surfaces of the ball race bars 118 and advance inwardly in the same horizontal plane toward one another, but do not actually contact in making the overlap, as shown in Fig. 25. The folder blade 204 projects forwardly from a carriage 211 mounted upon rollers 212 which ride within grooved tracks 213, and the carriage is 75 advanced and retracted by a thrust rod 214 piv-

oted at its forward end at the point 215 and connected at its rear end to the upper arm 216 of a bell crank lever 217 mounted at its elbow on a fixed pivot 218. The short lower arm 219 of the lever carries a roller 220 riding within the channeled face 221 of an arm 222 pivoted upon a fixed pivot 223.

The arm 222 has pivoted thereto a link 224 which is pivoted to the free end of a second link 225, which in turn has its rear end mounted upon a fixed pivot 226. The pivoted ends of the two links carry a roller 227 which rides within a cam groove 228 in a cam 229 mounted upon the cam shaft 65. Similarly, the folder blade 205 is secured to a carriage 230 mounted upon rollers 231 riding within the channeled faces 232 of tracks 233.

The carriage is actuated by spaced thrust rods 234, each of which is pivoted at its rear end to an arm 235, which arms are mounted upon a rock shaft 236, which in turn is actuated by a link 237 pivoted to the upper arm 238 of a bell crank lever 239 mounted upon the fixed pivot 218. The lower arm 240 of the bell crank lever carries a roller 241 which rides within the channeled face 242 of an arm 243 pivoted on a fixed pivot 244, and carrying a roller 245 which rides within a cam groove 246 in the face of a cam 247 mounted upon the cam shaft 65.

The rotation of the cams, through the transmission mechanism heretofore described, causes the folder blades 204 and 205 to advance and recede in timed relation in the manner illustrated by comparison of Figs. 23 and 25, and in conformity with the diagram shown in Fig. 10.

During the initial inward movements of the folder blades, the package will continue to rest upon the elevator 68, and the acting edges of the folder blades will slip in between the bottom of the package and the elevator and lift the package slightly from the elevator, which immediately thereafter will begin to descend so as to afford full clearance for the folding operation, the package meanwhile being supported upon the folder blades, and held in place thereon.

At the terminus of the folding movement, the folder blade 204 will have advanced completely beneath the package, as shown in Fig. 26, and will serve as a support therefor during the folding in of the side and bottom flaps presently to be described. Thereafter, the folder blade 204 will itself serve as an elevator to lift the package to its final discharging position. In order to permit the folder blade 204 to thus serve as an elevator, it is mounted in the manner shown in Figs. 22, 23, 25, and 29.

The grooved tracks 212 are carried in unison by a vertical frame comprising rods 248 connected at their upper ends by a cross head 249 and at their lower ends by a cross head 250, which rods roll upon grooved guide rollers 251 carried by the post 75.

Tucker mechanism

With the wrapper folded and overlapped to the extent previously described, it is necessary to first turn up the bottom projecting flaps against the ends of the package and thereafter tuck in the side flaps to an extent shown in Fig. 29 and in the fifth position from the left in the diagram of Fig. 10.

The L-shaped tucker blades 258 shown in Fig. 26 operate to tuck up the end folds from the bottom at each end of the package, the arrange-

ment being shown in duplicate. Each pair of tucker blades is carried by a rod 259 slidably mounted within a sleeve 260 and carrying a roller 261 at its lower end. The sleeves project inwardly from brackets 262 carried by heads 263 fixedly mounted upon the rear ends of adjustable guide bars 52 forming the part of the package feeding assembly and adjustable longitudinally therewith in a manner presently to be described, to accommodate packages of different width (Fig. 33). The tucker blades of a pair are themselves carried by slotted overlapping fingers 265 adapted to be locked by a thumb nut 266, so that the spread of the fingers may be adjusted as occasion requires, and the pairs of blades are adjustably mounted on the respective rods so that they may be adjusted toward and from one another to accommodate packages of different lengths. Three sets of tucker blades 258 of different sizes may be used interchangeably as occasion may require.

The duplicate tucker assemblies operating at each end of the package are actuated in unison by a horizontally disposed riser plate 267 which is of sufficient area to permit both longitudinal and transverse adjustments of the folder assemblies, without disturbing contact with the rollers 261. The riser plate is provided with a depending arm 268 which pivots a link 269, which in turn is pivoted at its rear end upon a fixed pivot 270 carried by an arm 271 carried by the post 75.

The arm 268 also has pivoted thereto the forward end of a swinging arm 272 which is fast to a rock shaft 273 journalled within the fixed arm 271, and the rock shaft has fixed thereto the forward end of a grooved arm 274, which in conjunction with the arm 272 constitutes a bell crank construction. The grooved arm 274 is oscillated by a roller 275 carried by an adjustable slide block 276 operating within a channel 277 in the arm 276, which is fixed on a rock shaft 278. The arm 278 mounts a roller 281 traveling within a cam groove 282 in the face of a folder cam 283 carried by the cam shaft 65.

The rotation of the cam oscillates the arm 278 and imparts a swinging movement through the grooved arm 274 and the rock shaft 275 to the arm 272 which elevates the plate 267. The surface of the plate, however, is at all times maintained in a horizontal plane by the link connection 269, so that uniform contact is maintained at all times with the rollers 261, which at the proper time elevate the tucker blade 258. The limit of the upward movement of the tucker blade is controlled by adjustment of the slide block 276 by means of an adjusting screw 278.

After the lower flaps have been tucked upwardly, the slide flaps are folded inwardly by tucker blades 284 and 285, shown in Fig. 27. These blades are carried respectively by riders 286 and 287 slidably mounted upon guide bars 288 and 289 respectively, and are removable, four sets being used interchangeably as occasion may require. In and out movements in unison are imparted to the riders through bell cranks 290 and 291, which are slotted at their lower ends 292 to engage pins 293 on the respective riders. Each bell crank, at its elbow, is mounted upon a fixed pivot 294. The pivot for the bell crank 290 is carried by a hanger 295 depending from a rod 296; and the pivot for the bell crank 291 is carried by a hanger 297 similarly mounted upon such rod.

The short upper arm of each of the respective

bell cranks is provided with a roller abutting the under side of a vertically movable operating bar 298 carried by spaced pivoted links 299 which permit up and down movements of the operating bar 298 while maintaining it in horizontal relation. As the operating bar moves upwardly, the short arms of the bell cranks will be elevated by suitable springs, thereby retracting the tucker blades in unison, and when the operating bar is lowered, the blades will be advanced inwardly in unison.

Vertical motion is imparted to the operating bar through a bell crank 300, which is pivoted at 301 to the operating bar and is movable about a fixed pivot 302. The rear end of the bell crank is connected to the upper end of a lever 303 which is medially pivoted at 304 to a link 305 freely mounted upon the rock shaft 273.

The lower end of the lever is pivoted at 306 to the arm 280, which carries the cam actuated roller 281, so that movements imparted from the cam 283 will be transmitted through the mechanism described to the vertically movable operating bar 298, which will actuate the bell cranks 290 and 291 in unison to tuck in the side flaps of the wrapper against the ends of the package.

It will be understood that the mechanism above described is duplicated at each end of the package, so that the operations described will be concurrently performed in unison by each tucker assembly.

Package delivery mechanism

The tucking operations heretofore described have been performed at the intermediate level, with the elevator folder blade 204 standing in its lowermost position, and immediately upon the completion of such tucking operations the cam mechanism and connections will operate to elevate the wrapped and partially tucked package to the upper level illustrated in Fig. 30. As the package is lifted, the upper end flaps of the wrapper will encounter the plates 204^a and be folded downwardly. Opposed swinging angle bars having inner edges 307 are mounted immediately above the plates 204^a which, as shown in Fig. 13, are in their retracted position to permit the lifting of the package.

Each of the angle bars 308 is provided with inwardly extending fingers 309 which are pivoted at 310 to fixed side guide plates 311 in position at the proper time to be swung inwardly as in Fig. 14 to engage the under end edges of the now completely wrapped and folded package, as in Fig. 14. After the package has been thus engaged and supported, the elevator folder blade 204 will descend and simultaneously be retracted along the dot and dash line indicated in Fig. 30, which line of travel enables its forward edge to clear the next succeeding package meanwhile being lifted by the elevator 68.

The upper edge of each of the swinging angle bars is provided with a bead or rib 312 which is obliquely downturned at its forward end 313 (Figs. 14 and 29), and this bead furnishes a trackway for upper and lower rollers 314 which are journaled upon a hanger 315. The duplicate hangers are carried by a bridge comprising a pair of spaced rods 316 supported upon their opposite ends upon riser brackets 317 carried in each case by a slidably mounted pusher rod 318, which rods serve to reciprocate the bridge, which carries pusher plates 319, which plates in unison serve to discharge the wrapped and tucked package from the position previously occupied and carry the same forward, as in Fig. 30, between

spaced heated sealing plates 320 located on opposite sides of the line of travel of the packages.

Upon the return movement of the bridge to bring the pusher plates to a position in advance 5 of the next arriving package, the carriage rollers 314 will ride under the obliquely downturned ends 313 of the ribs 312, which causes each of the angle plates to lift and swing outwardly on its pivotal mounting 310 to retract the inner edges

10 307 from the package supporting position shown in Fig. 14 to the clearing position shown in Fig. 13.

Reciprocating movements are imparted to the bridge through the rods 318, each rod being pivotally connected by a link 321 with the upper end 15 of a lever arm 322 fixed upon a rock shaft 323. One of the lever arms is extended to afford a short arm 324 carrying a roller 325, which rides within a groove 326 in the face of a pusher cam 327 mounted upon the cam shaft 65, so that as 20 the cam is rotated the rods 318 will be reciprocated in unison, thereby imparting back and forth movements to the pushers which advance the packages.

Adjustment in spacing of operating parts

25 In order to eliminate the inconvenience and time required in individually adjusting the various mechanisms to wrap packages of varying length and width and to insure that the various 30 operations will be properly timed and harmonized regardless of adjustment, the parts are mounted in a manner well illustrated in part in Fig. 33, which particularly illustrates the mountings required in making the longitudinal adjustments 35 required in adapting the machine to packages of varying width.

As seen in Fig. 33, the bars 54^b are carried at their inner ends by hangers 328 which depend on each side from head castings 329, each provided with a threaded block 330 which rides upon a screw rod 331 carrying a sprocket 332 at its forward end, which sprockets mount an endless sprocket chain 333. One of the screw rods at 40 its forward end mounts a hand wheel (Fig. 2), so that as the wheel is turned and the screw rods 45 331 rotate in unison, longitudinal adjusting movements will be imparted to the head castings 329 and the parts carried thereby, including the package feeding assembly at the forward end of the machine.

The head castings on each side carry the forward ends of spaced frame bars 334 which are connected at their rear ends by a bridge 335, which parts in conjunction constitute an upper 55 frame longitudinally adjustable as a unit in conjunction with the frame members carrying the package feeding assembly. The head castings also provide mountings for the ends of the forward bar 104, which carries the forward wrapper 60 conveying tape and the pulleys which mount the same, as well as the forward set of grid bars 118^a associated with said tape, so that the spacing of the tapes will be adjusted concurrently with the adjustment of the point of delivery of the packages carried rearwardly by the feed bars 48.

65 Between the head castings 329 are mounted the adjusting heads 67 (Fig. 33) through both of which extends a right and left screw 336 having its ends journaled within brackets 337 mounted upon a fixed cross head or cowl 338 (Fig. 2) forming part of the frame of the machine. The screw 336 carries a hand wheel 339 within convenient reach of the operator. The adjusting heads 67 carry the forward ends of spaced frame 70 bars 340, which carry castings 341 at their rear

ends, which mount pinions 341^a riding on a fixed rack 342 supported at the rear end of the machine. The pinions are carried by rods 343 mounting pinions 344 at their forward ends which engage a fixed forward rack 345 (Fig. 33), which pinion and rack arrangement serves to maintain the bars 340 and parts carried thereby in parallel relation as they are adjusted transversely in opposition to one another beneath the bridge rods 316. The frame bars 340 support the heat plates 320, and also the rods 296 which carry the hangers 295 and 297, so that these parts will partake of the transverse adjustments imparted by the rotation of the screw 336.

As the wrapped packages are advanced between the side heat plates 320 and an underlying heat plate 346, the folds and flaps will be heat sealed, and thereafter the packages pass over and between grid plates 347 and 348, so that excess heat will be withdrawn before they reach the delivery point.

Variable speed adjustment

In order to regulate the speed imparted to the cam shaft 65 by the motor 61, the mechanism shown in Figs. 3, 31 and 32 is employed. The motor shaft 349 carries a grooved pulley 350 which mounts a belt 351 tapered in cross section, which is carried around an adjustable pulley unit comprising heads 353 and 353^a freely mounted upon a shaft 354 and provided with staggered intermeshing fins 355 with oblique edges so disposed that in conjunction they will present a V-groove for the reception of the belt 351. The pulley head 353^a is double faced and is provided on its opposite face with a similar set of fins 356 meshing with fins 357 on the inner face of a pulley head 358, which in conjunction with the fins 356 afford a V-shaped groove for the reception of a belt 359.

The double faced pulley head 353^a is freely mounted upon the shaft 354 which carries a handle 360. The belt 359 is carried around a gear reduction assembly 361 in train through a sprocket chain 362 with the cam shaft 65. The pulley shaft 354 is provided with pinion teeth 363 at its opposite ends, which roll upon arcuate fixed racks 364 carried by hanger plates 365, the curvature of the racks being such that as the handle 360 is rotated in one direction or the other the belts 351 and 359 will assume a varying relation with respect to the axis of the pulley members, causing the intermediate double faced pulley head 353^a to shift its position longitudinally of the shaft under the tension of the belts, which thus correspondingly changes the drive ratio of the parts. After adjustment, the shaft may be locked in adjusted position by the tightening of a thumb screw 366.

Operation

In adjusting the positions of the operating parts, both longitudinally and transversely, to afford the proper space to accommodate packages of the intended dimensions, the adjustments will be imparted in proper degree to the cam actuated transmission elements which regulate the thrust of the tucker mechanisms and the extent of the web feeding and wrapper delivery mechanisms, so that, by the proper degree of rotation of the two hand wheels which effect adjustments and by employing an elevator and tucker plates of proper dimensions, the machine will be completely adjusted to operate in the intended manner and in harmonious timed rela-

tionship on packages of the required size. This is a highly important feature of the present invention, in that it insures a properly harmonized relationship of the operating parts, irrespective of adjustment, so that jamming or breakage due to faulty adjustment cannot occur, and great saving in time is effected whenever it becomes necessary to adjust the machine.

With the machine properly adjusted, and with 10 a roll of paper or the like of the proper width mounted upon the roll spindle and threaded up to the bite of the web feeding roll 101 and with the packages in position on the package feeding carrier to insure closing of the motor circuit, the 15 machine is set in motion at the intended speed, and the packages, in processional relation, will be fed forward by the engagement of the cross rods 48 of the carrier until the foremost package is thrust upon the elevator 68. Meanwhile a 20 severed wrapper section is being fed forward above the level of the package to the degree necessary to bring its folding center in proper relation with the geometric center of the package and with the ends of the wrapper held taut by 25 the weighted balls 117.

With the package and wrapper thus in register, the elevator will begin to rise, which draws the ends of the wrapper under tension from beneath the balls, and as the package is lifted, the 30 ends of the wrapper will be smoothly folded downwardly along the sides of the package and in position to be engaged by the folder blades 204 and 205, which operate in conjunction to overlap the end edges of the wrapper along the bottom 35 of the package. The folder blade 204 thereupon assumes the functions of a support and elevator, allowing the elevator 68 to descend while the projecting bottom and side flaps are folded inwardly across the ends of the package, allowing 40 the top flaps at this stage to project outwardly beyond the ends of the package.

It will be noted that the overlap folding and the end flap tucking operations previously referred to are all performed while the package 45 stands stationary at the intermediate level, after which the package is elevated by the folder blade 204 to the third or highest level, meanwhile sweeping down the projecting top end flaps as the package is being carried upwardly, so that 50 when the package reaches the highest level it will be in a completely wrapped condition and ready for the heat sealing operation. Thereupon the pusher plates 319 advance to discharge the package between the heat plates, which serve 55 to seal the flaps and thus complete the operation. As subsequent packages are delivered, the packages at the head of the procession will be forced forwardly by pressure from behind, which carries the procession of packages through the heat 60 sealing and cooling sections of the machine and delivers them at the discharge end thereof.

The machine as a whole is designed to insure the smooth, even wrapping and sealing of packages of any desired size within the capacity of 65 the machine, and the parts are so arranged that as the oncoming packages are delivered to the elevator 68 at the lowermost level, the folding, tucking and sealing operations will continue in progress at higher levels, which arrangement 70 greatly increases the speed capacity of the machine, since the elevator 68 will be enabled to descend to its lowermost position to receive an oncoming package without deferring its operation until the folding and tucking operations are 75 performed at the next higher level.

The machine as a whole is rugged in construction and certain in its timing, since all of the timing operations are initiated by the rotation of the cam shaft, which may be driven at the desired speed through the variable speed mechanisms described, or by any other suitable or convenient means.

Although the machine has been described in complete detail, it is not the intention in the claims to limit the construction to that here shown by way of exemplification, since the basic principles underlying the operation of the machine may find embodiment in machines displaying numerous modifications in detail, and particularly in variations in the transmission assemblies provided for imparting the required motions to the parts which perform the essential operations.

I claim:

1. In a wrapping machine, the combination of a package feeding carrier adapted to transport packages toward the wrapping position, means adapted to receive packages singly from the carrier and elevate the same by intermediate stages first to an intermediate wrapping position and after a period of rest to an uppermost position for discharge, means for advancing wrapper sections singly and adapted to position each wrapper section in overlying relation to a package when in its lowermost position with the ends and sides of the wrapper section projecting beyond the walls of the package, means coacting with the elevator means for folding down the projecting ends of the wrapper section along the sides of the package as the package is elevated to the intermediate wrapping position, means for performing folding and tucking operations on the projecting portions of each wrapper section, a portion of said means being operable at the intermediate level and the remaining portions being operable at a higher level, and power transmission connections for actuating the operating parts in properly timed relation to one another.

2. In a wrapping machine, the combination of a package feeding carrier adapted to transport packages toward the wrapping position, means adapted to receive packages singly from the carrier and elevate the same by intermediate stages first to an intermediate wrapping position and after a period of rest to an uppermost position for discharge, means for advancing wrapper sections singly transversely with relation to the line of advancement of the packages and adapted to position each wrapper section in overlying relation to the package when in its lowermost position with the ends and sides of the wrapper section projecting beyond the walls of the package, means coacting with the elevator means for folding down the projecting ends of the wrapper section along the sides of the package as the package is elevated to the intermediate wrapping position, means for performing folding and tucking operations on the projecting portions of each wrapper section, a portion of said means being operable at the intermediate level and the remaining portions being operable at a higher level, and power transmission connections for actuating the operating parts in properly timed relation to one another.

3. In a wrapping machine, the combination of a package feeding carrier adapted to transport packages toward the wrapping position, means adapted to receive packages singly from the carrier and elevate the same by intermediate stages first to an intermediate wrapping position and

after a period of rest to an uppermost position for discharge, means for advancing wrapper sections singly and adapted to position each wrapper section in overlying relation to a package when in its lowermost position with the ends and sides of the wrapper section projecting beyond the walls of the package, means adapted to effect a folding down of the projecting ends of each wrapper section along the sides of the package before the same reaches its intermediate wrapping position, folder and tucker mechanisms for first overlapping the folded down ends of the wrapper beneath the base of the package and thereafter tucking in the projecting portions of the wrapper against the ends of the package, said overlapping operations being performed at the intermediate position and said tucking operations being performed at least in part at a higher level, and power transmission means for actuating the operating parts in properly timed relation to one another.

4. In a wrapping machine, the combination of a package feeding carrier adapted to transport packages toward the wrapping position, means adapted to receive packages singly from the carrier and elevate the same by intermediate stages first to an intermediate position and after a period of rest to an uppermost position for discharge, means for advancing wrapper sections singly transversely with relation to the line of advancement of the packages and adapted to position each wrapper section in overlying relation to a package when the elevating means is in its lowermost position with the ends and sides of the wrapper section projecting beyond the walls of the package, means adapted to effect a folding down of the projecting ends of each wrapper section along the sides of the package during the elevation of the package to the intermediate position, folder and tucker mechanisms for first overlapping the folded down ends of the wrapper beneath the base of the package and thereafter tucking in the projecting portions of the wrapper against the ends of the package, the overlapping operations being performed at the intermediate position and said tucking operations being performed at least in part at a higher level, and power transmission means for actuating the operating parts in properly timed relation to one another.

5. In a wrapping machine, the combination of a package feeding carrier adapted to transport packages singly toward the wrapping position, an elevator adapted when lowered to receive packages singly from the carrier means to elevate the same to an intermediate wrapping position, mechanism for delivering wrapper sections in position to bring each wrapper section into overlying relation with respect to a package carried by the elevator when lowered and with the ends and sides of the section projecting beyond the walls of the package, means coacting with the elevator for folding down the projecting ends of the wrapper along the sides of the package before the elevator reaches the intermediate wrapping position, opposed folder blades, means to advance the folder blades inwardly at the intermediate position to overlap the folded down ends of the wrapper beneath the base of the package, one of the folder blades being mounted to thereafter move vertically to elevate the partially wrapped package to an uppermost wrapping position, tucker mechanisms and means to operate the same after the package has reached the intermediate wrapping position to tuck in the remain-

ing projecting portions of the wrapper section against the ends of the package, and power transmission mechanisms for actuating the various operating mechanisms in timed relation to one another.

6. In a wrapping machine, the combination of a package feeding carrier adapted to transport packages singly toward the wrapping position, an elevator adapted when lowered to receive packages singly from the carrier means to elevate the same to an intermediate wrapping position, mechanism for delivering wrapper sections transversely with relation to the line of advancement of the packages in position to bring each wrapper section into overlying relation with respect to a package carried by the elevator when lowered and with the ends and sides of the section projecting beyond the walls of the package, means coacting with the elevator for folding down the projecting ends of the wrapper along the sides of the package before the elevator reaches the intermediate wrapping position, opposed folder blades, means to advance the folder blades inwardly at the intermediate position to overlap the folded down ends of the wrapper beneath the base of the package, one of the folder blades being mounted to thereafter move vertically to elevate the partially wrapped package to an uppermost wrapping position, tucker mechanisms and means to operate the same after the package has reached the intermediate wrapping position to tuck in the remaining projecting portions of the wrapper section against the ends of the package, and power transmission mechanisms for actuating the various operating mechanisms in timed relation to one another.

7. In a wrapping machine, the combination of a package feeding carrier adapted to transport packages singly toward the wrapping position, an elevator adapted when lowered to receive packages singly from the carrier means to elevate the same to an intermediate wrapping position, mechanism for delivering wrapper sections in position to bring each wrapper section into overlying relation with respect to a package carried by the elevator when lowered and with the ends and sides of the section projecting beyond the walls of the package, means coacting with the elevator for folding down the projecting ends of the wrapper along the sides of the package before the elevator reaches the intermediate wrapping position, opposed folder blades, means to advance the folder blades at the intermediate position to overlap the folded down ends of the wrapper beneath the base of the package, one of the folder blades being mounted to thereafter move vertically to elevate the partially wrapped package to an uppermost wrapping position, tucker mechanisms adapted to tuck in the remaining projecting portions of the wrapper section against the ends of the package, a portion of the tucker mechanisms being positioned to perform the tucking operation at the intermediate wrapping position and a portion being positioned to effect a final tucking operation as the package is being elevated to the uppermost wrapping position, and power transmission mechanisms for actuating the various operating mechanisms in timed relation to one another.

8. In a wrapping machine, the combination of a package feeding carrier adapted to transport packages singly toward the wrapping position, an elevator adapted when lowered to receive packages singly from the carrier, means to elevate the same to an intermediate wrapping posi-

tion, mechanism for delivering wrapper sections transversely with relation to the line of advancement of the packages in position to bring each wrapper section into overlying relation with respect to a package carried by the elevator when lowered and with the ends and sides of the section projecting beyond the walls of the package, means coacting with the elevator for folding down the projecting ends of the wrapper along

5 the sides of the package before the elevator reaches the intermediate wrapping position, opposed folder blades, means to advance the folder blades at the intermediate position to overlap the folded down ends of the wrapper beneath the base of the package, one of the folder blades being mounted to thereafter move vertically to elevate the partially wrapped package to an uppermost wrapping position, tucker mechanisms adapted to tuck in the remaining projecting portions of the 10 wrapper section against the ends of the package, a portion of the tucker mechanisms being positioned to perform the tucking operation at the intermediate wrapping position and a portion being positioned to effect a final tucking operation as the package is being elevated to the uppermost wrapping position, and power transmission mechanisms for actuating the various operating mechanisms in timed relation to one another.

9. In a wrapping machine, in combination with feeding means for advancing packages to the wrapping position, a sub-combination consisting of, a conveyor for advancing wrapper sections singly to position to overlie a package delivered

35 by the package feeding mechanism, with the ends and sides of the wrapper section projecting beyond the walls of the package, pressure means cooperating with the wrapper delivery mechanism for applying pressure to the projecting ends 40 of the wrapper section, and means for imparting relative movement between the package and the wrapper section and transversely of the plane of the wrapper to smoothly fold down the ends of the wrapper section under tension around the 45 sides of the package as relative movement is imparted thereto, the conveyor including spaced tapes positioned to contact one of the faces of the wrapper section and the pressure means comprising rows of loosely caged balls aligned 50 with the associated tapes and adapted to contact the other face of the wrapper section and permit inward withdrawal of the ends of the section under pressure.

10. In a wrapping machine, in combination with feeding means for advancing packages to the wrapping position, a sub-combination consisting of, a conveyor for advancing wrapper sections singly and in transverse direction to the line of advance of the package to position to

60 register with a package delivered by the package feeding mechanism, with the ends and sides of the wrapper section projecting beyond the walls of the packages, spaced pressure means cooperating with the wrapper delivery mechanism for applying pressure to the portions of the wrapper section projecting beyond the side walls of the package, and means for imparting relative movement between the package and the wrapper section and transversely of the plane of the wrapper 65 to smoothly fold down the ends of the wrapper section under tension around the sides of the package as relative movement is imparted thereto, the conveyor including spaced tapes positioned to contact one of the faces of the wrapper section and the pressure means comprising rows

70 75

of loosely caged balls aligned with the associated tapes and adapted to contact the other face of the wrapper section and permit inward withdrawal of the ends of the section under pressure.

11. In a wrapping machine, the combination of a package feeding carrier adapted to transport packages singly toward the wrapping position, an elevator adapted when lowered to receive packages singly from the carrier, means to elevate the same to an intermediate wrapping position, mechanism for delivering wrapper sections transversely with relation to the line of advancement of the packages in position to bring each wrapper section into overlying relation with respect to a package carried by the elevator when lowered and with the ends and sides of the section projecting beyond the walls of the package, means coacting with the elevator for folding down the projecting ends of the wrapper along the sides of the package before the elevator reaches the intermediate wrapping position, opposed folder blades, means to advance the folder blades at the intermediate wrapping position to overlap the folded down ends of the wrapper beneath the base of the package, one of the folder blades being mounted to thereafter move vertically to elevate the partially wrapped package to an uppermost wrapping position, tucker mechanisms and means to operate the same after the package has reached the intermediate wrapping position to tuck in the remaining projecting portions of the wrapper section against the ends of the package, power transmission mechanisms for actuating the various operating mechanisms in timed relation to one another, interconnected adjusting mechanisms adapted to effect longitudinal adjustments in unison of the package feeding carrier and the means for imparting longitudinal movements to the folder blades and tucker mechanisms to adapt the machine to the wrapping of packages of different width, and interconnected adjusting mechanisms adapted to effect in unison coordinated adjustments in the means for advancing wrapper sections in the positioning of the tucker mechanisms to adapt the machine to the wrapping of packages of different length.

12. In a wrapping machine, the combination of a main frame, a package feeding carrier mounted thereon and adapted to transport packages toward the wrapping position and longitudinally adjustable to bring its discharge end to the desired position to accommodate packages of different widths, an elevator adapted to present a receiving surface in variable positions to accommodate packages of varying widths, and adapted when lowered to receive packages from the carrier, means for lifting the elevator to an intermediate wrapping position, means longitudinally adjustable in part for infeeding a wrapper to overlie a package supported on the elevator when lowered, means, adjustable as to longitudinal spacing, for folding projecting portions of the wrapper down along the sides of the package during the lifting of the elevator, folder means for infolding the down turned ends of the wrapper beneath the bottom of the package while in the intermediate wrapping position, a portion of said folder means being vertically movable to thereafter elevate the package away from the elevator and carry it to the uppermost position, tucker blades, laterally adjustable as to spacing for tucking in projecting portions of the wrapper upon the ends of the package while held in the intermediate wrapping position, a longitudinally

adjustable upper frame carried by the main frame to which the longitudinally adjustable elements, above enumerated are secured and means for adjusting the upper frame, hangers spaced within the upper frame to which the laterally adjustable elements are secured, means for adjusting the lateral spacing of the hangers, and transmission elements for actuating the operating parts in timed relationship and adjustable 10 conformably to the longitudinal and lateral adjustments of the operating parts.

13. In a wrapping machine the combination of a main frame, a package feeding carrier mounted thereon and adapted to transport packages 15 toward the wrapping position and longitudinally adjustable to bring its discharge end to the desired position to accommodate packages of different widths, an elevator adapted to present a receiving surface in variable positions to accommodate packages of varying widths and adapted when lowered to receive packages from the carrier, means for lifting the elevator to a higher level wrapping position, means, longitudinally adjustable in part, for infeeding a wrapper to 20 overlie a package supported on the elevator when lowered, means, adjustable as to longitudinal spacing for folding projecting portions of the wrapper down along the sides of the package during the lifting of the elevator, folder means 25 for infolding the downturned ends of the wrapper beneath the bottom of the package while in the higher level wrapping position, tucker blades laterally adjustable as to spacing for tucking in projecting portions of the wrapper upon the ends 30 of the package while held in the higher level wrapping position, a longitudinally adjustable upper frame carried by the main frame to which the longitudinally adjustable elements above 35 enumerated are secured and means for adjusting the upper frame, hangers supported from the main frame and adjustable transversely of the upper frame to which the laterally adjustable elements are secured, means for adjusting the lateral spacing of the hangers, and transmission 40 elements for actuating the operating parts in timed relationship and adjustable conformably 45 to the longitudinal and lateral adjustments of the operating parts.

14. In a wrapping machine, the combination 50 of a main frame, a package feeding carrier mounted thereon and adapted to transport packages toward the wrapping position and longitudinally adjustable to bring its discharge end to the desired position to accommodate packages of different widths, an elevator adapted to 55 present a receiving surface in variable positions to accommodate packages of varying widths and adapted when lowered to receive packages from the carrier, means for lifting the elevator to a higher level wrapping position, spaced endless 60 tapes, movable transversely of the machine and frames for carrying the tapes, one of the frames being longitudinally adjustable of the machine to vary the spacing between the tapes to accommodate the infeeding of wrappers of predetermined 65 lengths, to overlie a package supported on the elevator when lowered, means, adjustable as to longitudinal spacing for folding projecting portions of the wrapper down along the sides of the 70 package during the lifting of the elevator, folder means for infolding the downturned ends of the wrapper beneath the bottom of the package while in the higher level wrapping position, tucker blades laterally adjustable as to spacing for tucking 75 in projecting portions of the wrapper upon

the ends of the package while held in the higher level wrapping position, a longitudinally adjustable upper frame carried by the main frame to which the longitudinally adjustable elements above enumerated are secured and means for adjusting the upper frame, hangers supported from the main frame and adjustable transversely of the upper frame to which the laterally adjust-

able elements are secured, means for adjusting the lateral spacing of the hangers, and transmission elements for actuating the operating parts in timed relationship and adjustable conformably to the longitudinal and lateral adjustments of the operating parts.

JOHN A. HECKMAN.
